COMB

Charlie Adams Moore, Nashville, Tenn.

Application July 20, 1950, Serial No. 11,273

Term of patent 14 years

(Cl. D86—8)

To all whom it may concern:

Be it known that I, Charlie Adams Moore, a citizen of the United States, residing at Nashville, in the county of Davidson and State of Tennessee, have invented a new, original, and ornamental Design for a Comb, of which the following is a specification, reference being had to the accompanying drawing, forming part thereof.

4—4 of Figure 1 looking in the direction of the arrow.

I claim:

The ornamental design for a comb, substantially as shown.

CHARLIE ADAMS MOORE.
